UNITED STATES PATENT OFFICE

2,146,256

SMOKE CONDENSER AND COOLER

Charles Gobel, Philadelphia, Pa.

Application July 25, 1936, Serial No. 92,477

2 Claims. (Cl. 131—218)

The object of my invention is to devise a novel smoke condenser or cooler which can be used in conjunction with a pipe, cigarette or cigar.

A further object is to devise a novel smoke condenser and cooler wherein the following advantageous features are present:

1st. A dry, cool and refreshing smoke during the entire smoking period.

2nd. The elimination of any sogginess in the tobacco used in a pipe so that the tobacco will burn dry to the bottom of the bowl.

3rd. The elimination of throat irritation and the biting of the tongue.

4th. The elimination of the desire to freely expectorate.

5th. One may inhale freely with pipe, cigar or cigarette without coughing and expectorating.

6th. Causing the smoke to travel in proximity to a metal sleeve exposed to the atmosphere to obtain a maximum cooling and condensing action.

With the foregoing and other objects in view as will hereinafter more clearly appear, my invention comprehends a novel smoke condenser and cooler adapted for use with a pipe, cigarette or cigar.

It further comprehends a novel smoke condenser and cooler wherein the smoke travels in a circuitous path in forward and reverse directions between spaced sleeves of a character which will have a condensing and cooling action on the smoke passing from a pipe bowl, a cigarette or a cigar to the mouth piece.

It further comprehends a novel smoke condenser and cooler, wherein the smoke passes through ports between spaced sleeves towards the mouth piece, the outer of such sleeves being exposed to atmosphere, then rearwardly in the inner sleeve towards the end of such sleeve and then forwardly through a tube to the mouth piece.

Other novel features of construction and advantage, will hereinafter more clearly appear in the detailed description and the appended claims.

For the purpose of illustrating the invention, I have shown in the accompanying drawing a typical embodiment of it, which, in practice, will give satisfactory and reliable results. It is, however, to be understood that the various instrumentalities of which my invention consists can be variously arranged and organized, and my invention is not limited to the exact arrangement and organization of these instrumentalities as herein set forth.

Figure 1 is a sectional elevation of a pipe, in conjunction with which a smoke condenser and cooler embodying my invention is employed.

Figure 2 is an exploded view of parts of the smoke condenser and cooler.

Figure 3 is an enlarged sectional view of the smoke condenser and cooler showing the direction of travel of the smoke.

Similar numerals indicate corresponding parts.

Referring to the drawing:

The pipe has a bowl 1 and a stem 2 of any desired or conventional construction and contour.

The smoke condenser and cooler comprise three parts, namely; an outer tube 3, an intermediate tube 4, an inner tube 5, and a sleeve 6 which latter may be integral with or separate from the tube 5.

The outer tube 3 is connected at its forward end with the pipe bowl in any desired manner, and, as illustrated is provided with a reduced threaded tubular extension 7 adapted to be screwed into the stem of the pipe bowl. The tube 5 is threaded at its rear end as at 8 to adapt it to be screwed into the pipe stem 2.

The extension 7 of the outer tube or cylinder 3 may form a shoulder 9 to limit the forward movement of the tube 4 into the outer tube.

The tube 4 is closed at its forward end and is preferably dished to provide a chamber to receive the smoke which latter passes rearwardly from said chamber through the ports 10 and the space 11 formed between the outer wall of the tube 4 and the inner wall of the tube 3. The rear end of the tube 4 has a head 12 having longitudinally directed slots or ports 13 which at their rear ends open into the space 14 between the intermediate tube 4 and the inner tube 5. As this space is closed at its rear end by the end wall 15 of the sleeve 6, the smoke must now travel in a forward direction in the space 14 between the tubes 4 and 5. The tube 5 is open at both ends so that the smoke passes from the space 14 into the forward end of the inner tube 5 and rearwardly through said tube and through the mouth piece 2.

The parts of the condenser and cooler may be made of any desired or suitable material, but I have found in practice that very advantageous results are obtained if the parts, especially the outer sleeve 3 are made of metal.

The direction of travel of the smoke is clearly indicated by the arrows in Figure 3.

The intermediate tube 4 may have any desired outer wall construction to cause the smoke to pass around it to increase the condensing and cooling action.

I have found as a result of numerous experiments that an important condensing and cooling

action takes place in the chambers formed by the spaces 11 and 14.

Tobacco contains a certain amount of moisture and by condensing the moisture entrained in 5 the smoke and cooling the smoke, the latter as it passes through the mouth piece is cool and free from moisture and at the same time retains the natural flavor and aroma of the tobacco.

The nicotine contained in the moisture is con-10 densed and does not pass into the mouth of the smoker.

It will be clear from the foregoing, that the smoke is purified and the deleterious matter which is normally contained in smoke derived 15 from burning tobacco is eliminated.

Having thus described my invention, what I claim as new and desire to secure by Letters Patent is:

1. A smoke condenser and cooler having a 20 smoke inlet and a smoke discharge, comprising an outer, metallic, open ended tube exposed to the atmosphere, an intermediate metallic tube within and spaced from the inner wall of the outer tube, said intermediate tube having its 25 forward end closed and having ports at its outer periphery leading from the outer tube to the space between the tubes, the rear end of said intermediate tube having a ported shoulder, a sleeve within which said outer tube has a friction 30 fit and having a closed end, and an inner open ended metallic tube passing through the closed

end of said sleeve and positioned within the intermediate tube to form a forwardly extending space leading from the ports of said shoulder to the front open end of the inner tube, and said ported shoulder having its ports providing for both 5 longitudinal and radial travel of the smoke from the space between the outer and intermediate tubes to the space between the intermediate and inner tubes.

2. In a smoke condenser and cooler, an outer 10 metallic tube having a tubular inlet to receive the smoke and a shoulder in proximity to said inlet, an intermediate, metallic tube within and spaced from the wall of the outer tube and having a closed forward end contacting said shoul- 15 der, said closed end being provided with ports leading from the inlet of the outer tube to the space surrounding the intermediate tube, a tubu- 20 lar connecting member in frictional engagement with the outer tube and closing the discharge 25 end of the space between the outer and intermediate tubes, an inner, metallic tube carried by said member and spaced from the surrounding wall of the intermediate tube and also from its forward closed end, said intermediate tube hav- 30 ing ports forming a communication with the space between the outer and intermediate tubes and the space between the intermediate and inner tubes, and a mouth piece detachably connected with said member. 30

CHARLES GOBEL.
